UNITED STATES PATENT OFFICE.

H. CLAY BASCOM AND CYRUS A. HODGES, OF TROY, NEW YORK, ASSIGNEES
TO SAID BASCOM.

DESIGN FOR A COAL-STOVE.

SPECIFICATION forming part of Design No. 15,402, dated September 16, 1884.

Application filed June 17, 1884. Term of patent 7 years.

To all whom it may concern:

Be it known that we, H. CLAY BASCOM, and CYRUS A. HODGES, citizens of the United States, residing in the city of Troy, in the county of 5 Rensselaer and State of New York, have jointly invented and produced a new and original Design for Coal-Stoves, of which the following is a specification, reference being had to the accompanying cut, print, or engraving of a stove 10 having said design.

This invention relates to several new and distinct parts and combinations of parts which go to make up the whole design, as shown in the accompanying illustration, and hereinafter 15 specified.

One part of this design relates to the shape and ornamentation of the section D, consisting of the projecting rim d around its lower end, the upwardly-contracted convexly-curved part 20 e, having along its lower portion the row of alternating long and short upwardly-pointing ornaments j k, and the upwardly-contracted concavely-curved part f, having along its lower edge the series of upwardly-flaring ornaments l.

Another part relates to the shape and ornamentation of the fire-pot section C, the same being of circular downwardly-contracted form, and having along its upper part the series of 25 alternating long and short ornaments j' k', pointing downward.

Another part relates to the configuration and ornamentation of the door G, the same being of trapezoidal form, and having the border molding m, inwardly-flaring corner ornaments n, and the ornamented circular register o.

Another feature is the configuration and ornamentation of the base-section, consisting 40 of the quadrilateral bottom plate A, having the front extension with rounded corners a, and adjacent recesses b, and the quadrilateral upwardly-tapering portion B, having rounded corners, upper incline q, lower incline r, intermediate terrace-band c, ornamented top s, and circular inner rim t, the ornamental draft-plate u, and the cover v of the ash-pit opening.

The ornamental design for the legs consists

of the convexly-curved upper portion, w, having thereon the ornaments w' w'', the concavely-curved and contracted lower part, x, the angular foot y, and the top border, z, and side borders, z' z''.

The design for the main portion of the stove 55 embraces the configuration and ornamentation of the bottom plate, A, sections B C D E, top F, and door G.

The whole design embraces the configuration and ornamentation of the bottom plate, 60 A, sections B C D E, top F, door G, and the legs.

We claim as new—

1. In a design for a stove, the shape and ornamentation of the section D, consisting of 65 the part d, e j k, and f l, as shown and described.

2. In a design for a stove, the shape and ornamentation of the circular downwardly-contracted fire-pot section C, having the row 70 of ornaments j' k', as shown and described.

3. In a design for a stove, the configuration and ornamentation of the door G, embracing the parts m n o, as shown and described.

4. In a design for a stove, the configuration and ornamentation of the base-section, consisting of the plate A, having the parts a b, portion B, having the parts q r c, s, t, and the plates u and v, as shown and described. 75 80

5. In a design for a stove, the configuration and ornamentation of the legs, consisting of the parts w w' w'', x, y, and z z' z'', as shown and described.

6. In a design for a stove, the main portion, consisting of the parts A B C D E F G, shaped and ornamented as set forth.

7. The design for a stove, consisting of the parts A B C D E F G, and the legs, shaped and ornamented as set forth.

In testimony whereof we hereunto set our hands, in the presence of two subscribing witnesses, this 14th day of June, 1884.

H. CLAY BASCOM,
CYRUS A. HODGES.
